ARM-SUPPORTED SLINGSHOT

Albert H. Gauthier, Auburn, Maine, assignor of
one-half to Henry G. Lumbard, Auburn, Maine

Application December 22, 1952, Serial No. 327,381

4 Claims. (Cl. 124—20)

1

This invention comprises a new and improved sling shot having an arm rest whereby it may be effectively used for throwing hand grenades or any other missiles and in such a manner as to increase the range of the weapon and to steady it while under tension.

Sling shots as heretofore constructed have had the disadvantage that the great force imparted by the user to the tensioned bands must be resisted entirely by one hand and wrist alone. Consequently the pull of the sling has been limited, its range restricted and the weight of missiles discharged kept low. In the second place, since the hand and wrist holding the sling are under severe stress, it has been difficult to hold the aim accurately on a target. These objections are obviated and other advantages derived from the novel construction of this invention. Going more into detail it is now proposed to attach to the lower end of the handle of the sling shot a pair of longitudinal members diverging rearwardly and connected by an arcuate bridge in position to rest upon the forearm near the elbow of the user. Such a rest not only steadies the sling shot but transmits the pull of the bands to the arm of the user and so relieves his hand and wrist of excessive stress.

As an optional feature it is proposed to provide a pivotal connection between the sling shot proper and the arm rest so that these elements may be folded into compact relation for convenient storage and transportation.

These and other features of the invention will be best understood and appreciated from the following description of a preferred embodiment thereof in which—

Fig. 1 is a view in side elevation showing in solid lines the sling in operative position and in dot and dash lines the sling in collapsed position,

Fig. 2 is a view in front elevation,

Fig. 3 is a bottom plan view, and

Fig. 4 is a fragmentary plan view showing a connection between the sling and the arm rest.

The sling herein shown comprises a rod of spring steel formed to comprise forks 10 which terminate in eyes to receive the elastic bands 11 of the sling. The bands are joined by a section 12 which serve both as a receptacle for the missile and as a grip for the user. The forks 10 are brought together in a handle of parallel rods surrounded by a sleeve 13 which provides a secure and comfortable grip.

At the base of the handle the rods are bent forwardly in sections 14 and fashioned into a

2

rectangular base disposed at right angles to the handle of the sling. This base is secured by welding or otherwise to a rectangular stop plate 15 as well shown in Figs. 3 and 4.

5 The arm rest which will now be described is attached at its forward end to the front edge of the frame 14 and the stop plate by upstanding eyes 17. These eyes are formed in a pair of spring steel rods 16 which converge forwardly to 10 their point of pivotal connection with the frame 14 and diverge rearwardly for substantially the length of the user's forearm. They are spaced apart sufficiently to receive the forearm between them and connected at their rear ends by an 15 upwardly convex arcuate bridge 18 provided with a semi-circular sleeve 19 designed to fit the upper portion of the forearm. The bridge is of such height that the rods 16 of the rest are suspended by it slightly below the forearm as shown in Fig. 20 1, thus affording the user free wrist action.

When in operative position the stop plate 15 rests upon the forward ends of the steel rods 16 of the arm rest as shown in Fig. 1 supporting the sling shot proper at right angles to the arm rest. The user passes his left forearm through the bridge 18 and up between the rods 16, grasping the sleeve 13 of the handle in his left hand. He is now free to grasp the section 12 containing the missile with his right hand and to tension the bands 11. In this operation it will be 30 seen that the tensioning force applied to the bands 11 is transmitted to the user's forearm and resisted by downward pressure thereon of the bridge 18. At the same time the sling is steadied, being positively prevented from twisting in the 35 user's hand and supported by the rest.

When it is desired to collapse the weapon the sling with its frame 14 and stop plate 15 are merely swung forwardly and then rearwardly into the dot and dash portion shown in Fig. 1 wherein the body of the arm rest and the sling proper are disposed in adjacent parallel relation.

40 While for purposes of illustration the arm rest is shown as extending substantially at right angles to the forks 10 of the sling it is contemplated that the longitudinal axis of the arm rest 45 may be swung somewhat to one side or the other of the perpendicular according to whether the user is right or left handed. Such adjustment may serve to improve the position of the forks for a straight line pull upon the elastic bands 11.

It is also contemplated that when the weapon 50 is used for throwing hand grenades the locking pin may be pulled by temporary connection with the section or receptacle 12 from which the

grenade is launched. Such an arrangement will give the thrower ample time to aim the sling before he is ready to discharge the grenade and without being hurried by the knowledge that the pin has already been pulled.

Having thus disclosed my invention and described in detail an illustrative embodiment thereof, I claim as new and desire to secure by Letters Patent:

1. An arm-supported slingshot comprising an upright handle carrying a fork at its upper end for the attachment of elastic bands, and an arm rest extending at right angles to the handle from its lower end, the arm rest consisting of a pair of longitudinal members diverging rearwardly from the handle and spaced apart to receive the forearm between them, and an articulate bridge connecting the longitudinal members in position to rest upon the forearm near the elbow of the user and to suspend the longitudinal members below the forearm. 20

2. An arm-supported slingshot comprising a fork having a depending handle, and an arm rest attached to the lower end of the handle and consisting of a pair of spring-steel rods closely adjacent to each other at the handle and diverging from each other as they extend away from the handle and spaced apart to receive the forearm between them, and an upwardly extending convex bridge connecting the divergent ends of said rods at a distance from the han- 30

dle approximating the length of the user's forearm and being of such height as to suspend the steel rods of the arm rest below the forearm.

3. An arm-supported slingshot as described in 5 claim 2 in which the rods of the arm rest are pivotally connected to the lower end of the handle so that the fork with its handle may be folded into compact relation beneath the arm rest.

4. An arm-supported slingshot comprising a 10 fork having a depending handle with a stop face secured to the lower end of the fork, an elongated arm rest coextensive with the forearm of the user, and a hinge connecting the fork and arm rest whereby the handle may be folded beneath the arm rest or swung into an upright position in which said stop face contacts the outer portion of the arm rest and holds the fork and handle at substantially right angles to the arm rest. 15
